(57) **CLAIM**

(21) Appl. No.: **29/292,986**

The ornamental design for an exterior surface configuration
of a front vehicle light, as shown and described.

(22) Filed: **Nov. 7, 2007**

DESCRIPTION

(51) **LOC (8) Cl.** **26-06**

FIG. 1 is perspective view from the front left of an exterior
surface configuration of a front vehicle light. The drawings
and descriptions represent the right side embodiment. The
design also contemplates a mirror symmetrical embodiment
on the left side of the vehicle. The dash line included denotes
environment and is not part of the claimed design,

(52) **U.S. Cl.** **D26/28**

FIG. 2 is a front elevation view thereof;

(58) **Field of Classification Search** D26/28-36;
362/459-468, 475-478, 485-487

FIG. 3 is a left elevation view thereof; and,

See application file for complete search history.

FIG. 4 is a top view thereof.
